UNITED STATES PATENT OFFICE.

CHAPIN C. BROOKS, OF LANCASTER, NEW HAMPSHIRE.

DESIGN FOR AN AX-BLADE.

SPECIFICATION forming part of **Design No. 15,157**, dated July 22, 1884.

Application filed May 1, 1884. Term of patent 14 years.

To all whom it may concern:

Be it known that I, CHAPIN C. BROOKS, of Lancaster, in the county of Coos and State of New Hampshire, have invented and produced 5 a Design for an Ax-Blade, of which the following is a description.

The novel feature of this design is the configuration of the ax-blade, as hereinafter described, and shown in the accompanying drawing, which forms part of this specification, and represents a view in perspective of an ax-blade having my new design.

A is the ax-blade, either upper side edge, a, of which is of convex form, and either front 15 side edge, b, of straight configuration, inclining forward in a downward direction, while each of its back or inner side edges, c, is of concave shape, spreading backward in a downward direction. The bottom or cutting edge

of the blade presents the figure of a double or 20 reverse incline composed in part of nearly straight or slowly-convex lines d d, converging toward one another in a downward direction, and meeting or joined in the center of the width of the blade in or by a convex line, 25 e, of shorter radius than the lines d d.

I claim—

In an ax-blade, the design herein described, which consists in the blade the lower edge of which has straight lines d extending from the front and back walls downward toward the center, where they are joined by the convex line e, as shown.

CHAPIN C. BROOKS.
